US00D887985S

(12) **United States Design Patent** (10) Patent No.: **US D887,985 S**
Yamamoto (45) Date of Patent: **** Jun. 23, 2020**

(54) **AUXILIARY POWER OUTLET PLUG-IN CHARGER**

(71) Applicant: **Scosche Industries, Inc.**, Oxnard, CA (US)

(72) Inventor: **Yasuhiro Yamamoto**, Thousand Oaks, CA (US)

(73) Assignee: **Scosche Industries, Inc.**, Oxnard, CA (US)

(**) Term: **15 Years**

(21) Appl. No.: **29/670,554**

(22) Filed: **Nov. 16, 2018**

(51) LOC (12) Cl. **13-03**

(52) U.S. Cl.

USPC **D13/144**

(58) **Field of Classification Search**

USPC D13/144, 107, 108, 110, 118, 119, 120, D13/133, 154, 184, 199; D14/155, 217, D14/433

CPC H01R 24/58; H01R 2201/26; H01R 31/02; H02J 7/0042

See application file for complete search history.

(57) **CLAIM**

The ornamental design for an auxiliary power outlet plug-in charger, as shown and described.

DESCRIPTION

FIG. 1 is a front perspective view showing an auxiliary power outlet plug-in charger of the present invention;

FIG. 2 is a rear perspective view thereof;

FIG. 3 is a top view thereof;

FIG. 4 is a left side view thereof;

FIG. 5 is a right side view thereof;

FIG. 6 is a bottom view thereof;

FIG. 7 is front view thereof; and,

FIG. 8 is a rear view thereof.

In the drawings, the broken line showings are for purposes of illustrating environmental structure or portions of the auxiliary power outlet plug-in charger that form no part of the claimed design.

1 Claim, 3 Drawing Sheets
